UNITED STATES PATENT OFFICE.

FREDERICK V. WINTERS, OF NEW YORK, N. Y.

VACUUM-CREATING INSTRUMENT.

Application filed February 9, 1925. Serial No. 8,073.

The invention relates to vacuum creating instruments, and has for its object to provide a device of simple construction, easily operated to create a vacuum space.

5 A further object is to provide a device that will reduce the atmospheric air therein or in a jar containing preserves, or the like, at the time of operating the device.

10 A further object of the invention is to provide a device of this character adaptable especially for use where culinary operations are moderately carried out, and where in the same may be efficiently operated without the exercise of special knowledge or 15 skill.

A further object is to provide a device of this character, featured by the lack of complicated parts and mechanism, which involves but few parts, all so constructed and 20 assembled as to minimize the opportunity for wear, breakage or derangement, which may be easily cleaned and at all times maintained in sanitary condition, and which will prove highly effective in use.

25 In the drawings:

Figure 1 is a vertical sectional view taken through a vacuum creating instrument constructed in accordance with the invention and illustrating the parts in the position 30 they will assume when the device is ready for operation;

Figure 2 is a similar view showing the parts in the position they will assume just prior to the breaking of the vacuum seal; and

35 Figure 3 is a top plan view of the improved vacuum creating instrument.

Referring now more particularly to the drawings, the invention is carried out by the use of a shell 4, which may be termed 40 the inner shell or receiving compartment, the same being of substantially cup shape with the side walls thereof disposed preferably at right angles to the base. This shell is surrounded by a liquid column, the 45 same being established and maintained by providing an exterior or outer shell 5 for the inner shell. The outer and inner shells are concentric with each other so as to provide a space of equal breadth entirely around 50 the inner shell. The shells thus assembled may be secured to a suitable base or platform 6 by passing screws, bolts or other retaining implements 7 downwardly through the bottoms of the said shells and anchoring the 55 same in the base 6. The latter is recessed in its under face as at 8 to accommodate the

nuts 9 of the bolts, and gaskets or washers 10 may be introduced between the nut and base of recess 8 and between the head of the bolt and the bottom of shell 4, so that these 60 gaskets, preferably of rubber, will make a liquid and air-tight seal at the point of connection of the shells with the base. The inner shell 4 may have a pad 11 of soft material positioned in the base thereof and 65 upon which the jars 12 of glass or other material may rest. Such a pad affords a proper support for the jars and prevents breakage of the same should they be accidentally dropped. The under face of pad 70 11 may be recessed as at 13 for the accommodation of the heads of bolts 7.

Associated with the nested shells thus described is a dome or bell 14. This dome is substantially similar in construction to the 75 shell 4—5, being of slightly greater diameter than the inner shell and of slightly less diameter than the outer shell. This dome 14 is disposed in inverted position over the nested shells so that the side walls 80 thereof extend down into the space between shells 4—5.

The upper end or head of the dome 14 is provided with a valve 15 of such character as to permit escape of air from beneath the 85 dome when the latter moves down, but prevents air gaining access to the interior of the dome when the latter is moved upwardly. Various forms or types of one-way or check valves may be used for this result, and the 90 valve 15 herein disclosed is of conventional type. The upper end or head of the dome is provided with a handle 16 for convenience in handling.

The dome 14 is provided upon its sides at 95 diametrically opposite points with outwardly extended headed studs 17, carried by blocks 18 secured to the sides of the dome, and these studs are adapted to be engaged from beneath by the outer extremities of the 100 yoke represented at 19. This yoke is pivoted as at 20 to the upper ends of standards or supporting members 21, and the opposite end of the yoke is provided with an operating handle 22. The upper surfaces of the yoke arms 19 may be channeled or recessed as at 23 to permit the removal of dome 14, and a limited degree of lateral sliding movement of studs, 17, while the dome is being operated.

110 In operating, the jar containing the commodity to be preserved, is placed within the

shell 4. The cover of this jar is provided with a valve, such as represented generally at 24. This valve permits of air escaping from the jar, but is readily seated and seals the opening in the cover when the atmospheric pressure presses downwardly upon the said valve, as the dome 14 is being moved upwardly and vacuum is present in said dome. The valve herein shown is for the purpose of illustration only, and such valves may assume forms or constructions. The space between shells 4—5 is then supplied with a suitable or predetermined quantity of liquids, such as water, whereupon the dome 14 is moved downwardly, so that the edges thereof enter the space between the shells 4—5 and extend into the liquid, the latter represented at 25. During this downward movement, nearly all the air trapped, or in said dome will escape through the said valve 15. The ends of the yoke 19 are then engaged beneath the studs 17, and downward movement is applied to the handle 22. This causes the yoke to move upwardly, carrying with it the dome 14. This upward movement of dome 14 enlarges the vacuum space within the chamber thus formed, by shell 4, and as the dome 14 is raised or moved upward, said space is correspondingly increased.

Due to this result, air in the jar 12 passes out through valve 24 into the vacuum space surrounding said jar. The reduced atmospheric pressure and the created vacuum in said dome 14, causes the outside atmospheric pressure to exert its natural force upon the surface of the liquid 25, and said liquid will be forced downward between shell 5, and the dome wall 14, and upward between shell 4 and the interior dome wall, as shown particularly in Figure 2, at the instant the lower edge or end of said dome 14 is raised above the liquid seal 25, the normal atmospheric pressure causes atmospheric air to enter said created vacuum space between the interior wall of dome 14 and the exterior wall of shell 4, and closes and retains closed, valve

24, thus sealing the jar 12, and destroying all vacuum; the liquid 25 then gravitates to the position shown in Figure 1, at 25, and the dome 14 and jar 12, may then be removed without effort or interference, and the vacuum creating instrument is then ready for a repetition of its functions.

It is apparent that, while the foregoing is a description of the invention in its preferred embodiment, variations in the details of construction of the cups or shells and dome, their manner of assemblage and operation, may be liberally resorted to, without departing from the spirit of the invention, as defined by the claims.

Having thus described my invention, what I claim is:

1. A vacuum creating device comprising an inner shell for inclosing a preserving jar, an outer shell surrounding said inner shell, defining a space therebetween adapted to be partly filled with a sealing fluid, and a dome inclosing said inner shell and adapted to be reciprocated in said space and normally having its lower edge submerged in said sealing fluid, the elevation of said dome operating to break the liquid seal when the bottom edge thereof is raised above the level of the fluid in the space between said dome and said outer shell.

2. A vacuum creating device comprising an inner shell for inclosing a preserving jar, an outer shell surrounding the inner shell, defining a space therebetween adapted to be partly filled with a sealing fluid, a dome inclosing said inner shell and adapted to be reciprocated in said space and normally having its lower edge submerged in said sealing fluid and means for elevating said dome, said dome upon elevation having its bottom edge coacting with the level of the fluid in the space between said dome and said outer shell to break said liquid seal.

In testimony whereof I have signed my name to this specification.

FREDERICK V. WINTERS.
